UNITED STATES PATENT OFFICE.

WILLIAM A. SCHURMANN, OF PHILADELPHIA, PENNSYLVANIA.

EGG-BOX.

1,156,436.

Specification of Letters Patent.

Patented Oct. 12, 1915.

Application filed August 3, 1914. Serial No. 854,603.

To all whom it may concern:

Be it known that I, WILLIAM A. SCHURMANN, a citizen of the United States of America, and resident of Philadelphia, 5 Philadelphia county, Pennsylvania, have invented a certain new and useful Improvement in Egg-Boxes, of which the following is a specification.

My invention relates to egg boxes or cartons of that kind in which a flexible cover is provided and formed with a flap or lip which is inserted inside of the front wall of the box or carton after the latter is filled with eggs. Ordinarily, the said flap or lip 10 is inserted between the said front wall and the filler which is usually employed for holding the eggs in place.

The principal object of my invention is to provide an integral sealing tab for the 20 cover of a box or carton of this kind, having means for holding it in the plane of the flap or lip while the box is being manipulated, but the said means being adapted to be broken as soon as it is desired to seal the box, 25 the breaking of said means (which may consist of a small portion of the paste board or other material from which the box is made) permitting the tab to swing outward and into position to be glued or otherwise fastened to the outer surface of the front wall 30 of the box, thereby securely holding the cover in closed position.

To the foregoing and other useful ends my invention consists in matters hereinafter 35 set forth and claimed.

In the accompanying drawings—Figure 1 is a perspective of an egg box or carton provided with a sealing tab embodying the principles of my invention, the said box or 40 carton being shown with its cover in closed position, and with the said tab glued or otherwise fastened to the outer surface of the front wall of the box. Fig. 2 is an enlarged fragmentary view of a portion of the 45 cover of said box or carton, showing the tab with its retaining portion unbroken, whereby said tab is maintained in the plane of the flap or lip of the cover until such time as it is desired to seal the box, thus precluding 50 any accidental or premature bending of the tab, and preventing it from getting in the way while the box is being manipulated previous to and during the filling of the same. Fig. 3 is a section on line 3—3 in Fig. 2, 55 indicating in dotted lines the position of the

tab after its retainer is broken and after the tab is swung outward.

As thus illustrated, my invention comprises a foldable box or carton having a front wall A and a cover B, the said box 60 being rectangular in shape. The back wall and bottom of the box are flat, and the ends C have creases or fold lines c, whereby the said ends fold inward upon the bottom of the box. For this purpose, the front wall A is also provided with oblique creases or fold lines a which permit the said front wall to fold inward upon the bottom of the box. The said ends fold upon the front wall, and then the back wall folds down upon the 65 said ends; and the cover B extends forward with its flap or lip b, all substantially in a horizontal plane. The said flap b extends inside of the front wall A, when the box is closed, and is usually inserted between this 70 wall and the well known filler by which the eggs are held in place.

My invention relates to the method of sealing the said cover B in closed position. For this purpose, a tab b¹ is cut from the 80 central portion of the said flap or lip b, but the lower edge of this tab is not entirely separated from the adjacent portion of the paste board, being retained in the plane of the said flap or lip by a small portion b² of 85 the paste board. During manipulation of the box this retainer b² holds the tab b¹ against premature bending or displacement, and prevents the tab from getting in the way or interfering with the operation of 90

filling and closing the box. When the cover is brought downward, and before the flap or lip b is inserted inside of the front wall, the retaining portion b² is broken, thus allowing the tab b¹ to slide down outside of the front wall A, as shown in Fig. 1; and by means of glue or some other adhesive, the said tab can then be secured in place upon the outer surface of the said front wall. This adhesive can be previously applied to 95 the said tab, so that a moistening of the same will render it suitable for application to the surface of the front wall. But I do not limit myself to any particular means for securing the tab b¹ to the outer surface 100 of the front wall A, for the purpose of sealing the box, as this can be accomplished by mechanical means or fastening devices as well as by an adhesive.

From the foregoing it will be seen that 110

by my invention I provide an integral sealing device for securing the cover of the box in place. It will also be seen that this sealing device is effectively retained in an inoperative condition until wanted, and is then easily displaced from its position in the plane of the cover flap or lip, so that it may be applied to the outer surface of the front wall of the box. The entire box, it will be understood, is preferably of paste board, so that the said tab is flexible in character, it being movable about the fold line b^3 along which the flap or lip b is folded at right angles to the body of the cover. As shown, the said tab b^1 has the shape of a half moon, but it may be of any suitable form, and I do not limit myself to the exact construction shown and described.

What I claim as my invention is:—

- 20 1. In a paper box, a cover provided with a flap on its front edge adapted for engagement with the inner side of the front wall of the box and having a sealing tab formed therein, said sealing tab having a hinge connection and a readily breakable connection with said flap, whereby a partly formed tab is provided which will retain its alinement with said flap until the breakable connection is separated.
- 25 2. In a paper box, a cover provided with a flap on its front edge adapted for engagement with the inner side of the front wall

of the box and having a sealing tab formed therein, said sealing tab having a flexible connection with said cover on the folding line of said flap to form a hinge, and having a readily breakable connection with the body of said flap, whereby a partly formed tab is provided which will retain its alinement with the body of the flap until the breakable connection is separated.

3. In a paper box, a cover provided with a flap on its front edge and having a sealing tab formed therein, said flap adapted to be bent at right angles to said cover to engage the inner face of the front wall of the box, and said tab being formed by cutting through said flap in a plurality of places leaving a long connection with said cover on the bending line of the flap to form a hinge, and a breakable connection with the body of the flap, whereby said flap can be bent without dislocating the tab therefrom in order that the tab may be positioned with the flap, and said breakable connection separated to permit fastening of said tab and use thereof as a sealing member against the outer face of said front wall.

Signed by me at Philadelphia, Pennsylvania, this 20th day of July 1914.

WILLIAM A. SCHURMANN.
